UNITED STATES PATENT OFFICE

ARTHUR WURDACK, OF NORMANDY, MISSOURI

CHAIR

Application filed May 12, 1926. Serial No. 108,526.

This invention relates to improvements in chairs and consists of the novel construction hereinafter disclosed.

An object of the invention is to provide a chair primarily for outdoor or lawn purposes and it includes an adjustable back having means for supporting the back and seat member upon a flexible support with provision for effecting the adjustment of the back member. 10 Additional advantages of the construction will be apparent from the following detailed description of the invention, taken in connection with the accompanying drawings, in which,

15 Fig. 1 is a plan view of the chair with the back in an intermediate position.

Fig. 2 is a front elevation.

Fig. 3 is a side view showing the back in dotted lines in upright position and in full 20 lines in intermediate position.

Fig. 4 is a rear elevation.

Fig. 5 is a section through the chair with the back in an extended position.

Fig. 6 is a detail view showing the manner 25 of mounting the slats that constitute the back and seat portion.

In the embodiment of the invention illustrated in the drawing, the frame of the chair includes front legs 1. The front legs 1 are 30 braced by a cross member 2 extending transversely between said legs and near the bottom thereof. Attached to the inner sides of the legs 1 are side members 3 that incline downwardly and have their lower marginal edges 25 running horizontally in the plane of the lower ends of the legs 1 so that the chair may be mounted upon any plane support. Attached to the outer sides of the members 3 and near their rear ends are uprights 4 constituting the rear support for the chair frame. A cross member 5 extends transversely between the members 4 at an intermediate point in their height and serves to brace the frame of the chair laterally. Attached to the inner side of 40 each of the members 3 and between the members 1 and 4 are vertical blocks or cleats 6 which are connected by a transverse member 7 providing an intermediate support for the frame of the chair.

50 To the outer side of each of the members 1

and 2 and extending longitudinally thereof is a bracket 7. Said brackets 7 and the upper ends of the members 1 and 4 constitute supports for arm rests 8 extending from a point forward of the frame of the chair approximately horizontally to a point well in the rear thereof. Said arm rests are provided with studs 9 in lateral alinement disposed somewhat forward of the rear end of said rests. The studs 9 cooperate with a retaining member 55 for holding the back section in upright position, as will be explained in further detail hereinafter. 60

The frame for the back of the chair includes two side members 10, each of which is pivoted to the upper end of the respective block or cleat 6 by a pivot pin or bolt 11. Extending transversely between the said members 10 and at the upper extremity thereof 65 is a cylindrical member 12 fastened securely 70 in said side members at each end.

At the forward part of the frame of the chair and securely attached to the front face of the legs and at an elevation for the height of the seat of the chair is a cylindrical member 13. The seat and back members are a continuous section comprising a plurality of slats 14 that are mounted on spaced cables 15, the cables passing through openings near each end of the slats and the slats being spaced 80 by intermediate spacing washers 16, the construction being particularly shown in Fig. 6 of the drawing. The cables 15 are fastened at opposite ends to the members 12 and 14 respectively, preferably being secured thereto 85 by wrapping the ends about said members and permanently attaching the ends thereto.

In order to hold the continuous section of slatting so as to form the seat and back members, the upper ends of heavy retractile 90 springs 17 are connected to cables 15, while the lower ends of said springs are connected to the sides of the frame of the chair by pins 18 supported by and near the lower ends of blocks 6. The tendency of the springs 17 is 95 to hold the seat section taut in an inclined position and to hold the back member taut regardless of its adjustment. This unitary seat and back member is resilient and flexible, being resilient in a longitudinal direc- 100

tion by reason of the flexibility of the cables supporting the separate slats. The spacing washers 16 are preferably made of pliable material, such as leather or rubber, so that there is a slight lateral tilting thereof under 5 compression stresses. The whole structure forms an extremely comfortable support adjusting itself readily to the curvature of the body of the user.

The back member, in the embodiment 10 shown, is capable of three adjustments, although it will, of course, be understood that additional adjustments, by provision of additional stops 9, may be obtained. The adjustable support for the back comprises brackets 15 19 depending from the rear of the side members 10 of the back frame. Each of the brackets 19 has a longitudinal slot 20 and in the upright and intermediate positions of the back, the support includes a rod or pole 21 20 that extends through the longitudinal slots in the brackets 19, said member 21 projecting over the inner edges of the members 8.

In the upright position shown in dotted 25 lines in Fig. 3, it will be noted that the ends of the member 21 are positioned against the front sides of the pins or stops 9. In the intermediate position shown in full lines in this view, the ends of the member 21 rest directly 30 against the upper side of the members 8 and near the rear thereof.

In the reclining or extended position of the back, the back member is supported by a bail that comprises links 22, the upper ends of 35 which are pivoted to brackets 23 secured to the underside of the members 8 near the rear. A cross bar or rod 24 extends transversely between the free ends of the links 22. In effecting the extended adjustment of the back, 40 the member 21 is removed and the lower edges of the brackets 19 rest directly upon the member 24. By swinging the bail, a slight difference in the extended position may be obtained to provide a comfortable adjustment of the 45 seat and back member.

If desired, the chair may be provided with a foot rest comprising members 25 mounted in supports 26, attached to the inner sides of the side members 3 near the front legs and in 50 supports 27 attached rearwardly to the same side members, the alignment of the openings in the supports 26 and 27 being inclined so that the foot rest may be moved forwardly and upwardly in its extended adjustment.

55 A transverse member 28 extends between the two supports 27 and in order to prevent the foot rest from being entirely withdrawn, a stop pin 29 is mounted in the rear end of each of the members 25. The forward ends of 60 the members 25 support a suitably formed cross member 30. When in the inner adjustment, the vertical face of the foot rest 30 is disposed beneath the front edge of the seat member and flush with the front faces of the 65 legs 1. The lower edge of the vertical face of

the foot rest 30 is undercut to provide means for engaging it for the purpose of effecting the desired adjustment thereof.

It will be understood that the structure is so made that it is suitable for outdoor use, although it will, of course, be understood that it is not limited to such purposes. I am aware that the invention may be modified in various particulars without departing from the spirit and scope thereof.

What I claim and desire to secure by Letters Patent is:—

1. A chair comprising a pair of front and a pair of rear supporting legs, an arm rest connecting the front and rear legs at each side of the chair and extending rearwardly beyond the rear legs, a side member connecting the front and rear legs at each side, a back frame pivoted to said side members, a continuous flexible seat and back member having its front end connected to said front legs and its rear end connected to the upper end of said back frame, an element arranged to engage said arm rests and support said back frame in different angles of inclination, 90 and a bail supported by said arm rests for supporting said back frame in another angle of inclination.

2. A chair comprising a pair of front and a pair of rear supporting legs, an arm rest connecting the front and rear legs at each side of the chair and extending rearwardly beyond the rear legs, a side member connecting the front and rear legs at each side, a back frame pivoted to said side members, a continuous flexible seat and back member having its front end connected to said front legs and its rear end connected to the upper end of said back frame, an element arranged to engage said arm rests and support said back frame in different angles of inclination, 95 and a bail supported by said arm rests for supporting said back frame in another angle of inclination, and springs connecting said seat and back member with said side members 100 near the plane of the pivotal connection of said back frame with said side members.

3. A chair comprising a stationary frame, a back frame having its lower end pivoted to the stationary frame, a bail supported by said stationary frame, a device engageable on and removable from said stationary frame, and a pair of brackets attached to said back frame and cooperative with said bail or with said device optionally to support said back frame 110 to different angles of inclination.

ARTHUR WURDACK.
